(57) **CLAIM**

The ornamental design for a folding dry erase board, as shown and described.

DESCRIPTION

FIG. 1 is a perspective view of a folding dry erase board, in an opened condition, according to the present invention; FIG. 2 is a front view of the folding dry erase board illustrated in FIG. 1, the rear view being the mirror image thereof;

FIG. 3 is a back view of the folding dry erase board illustrated in FIG. 1;

FIG. 4 is a top view of the folding dry erase board illustrated in FIG. 1;

FIG. 5 is a bottom view of the folding dry erase board illustrated in FIG. 1;

FIG. 6 is a left side view of the folding dry erase board illustrated in FIG. 1;

FIG. 7 is a right side view of the folding dry erase board illustrated in FIG. 1; and,

FIG. 8 is a perspective view of the folding dry erase board, shown in a folded condition.

The structure depicted by means of broken lines in the figures has been shown for illustrative purposes only and forms no part of the claimed design.
